UNITED STATES PATENT OFFICE.

ALBERT TROLLER, OF ROCKFORD, ILLINOIS, ASSIGNOR TO THE ROCKFORD WATCH COMPANY, OF SAME PLACE.

STEM WINDING AND SETTING WATCH.

SPECIFICATION forming part of Letters Patent No. 408,274, dated August 6, 1889.

Application filed March 30, 1889. Serial No. 305,435. (No model.)

To all whom it may concern:

Be it known that I, ALBERT TROLLER, residing at Rockford, in the county of Winnebago and State of Illinois, and a citizen of the 5 United States, have invented a new and useful Improvement in Stem Winding and Setting Watches, of which the following is a specification, reference being had to the accompanying drawings, in which—

- 10 Figure 1 is a plan showing the inside of the top plate and the barrel-bridge in a case. Fig. 2 is a plan showing the inside of the top plate. Fig. 3 is a plan showing the outside of the top plate and the winding and setting mechanism in view. Fig. 4 is an under side view of the barrel-bridge. Fig. 5 is a perspective of the barrel-bridge and some other parts. Fig. 6 is a sectional view at line 6 of Fig. 1. Fig. 7 is a section at line 7 of Fig. 3. Fig. 8 is the 15 same as Fig. 7, showing some of the parts in a different position. Fig. 9 is a detail, being a section of the parts shown, taken at line 9 of Fig. 3. Fig. 10 is the same as Fig. 9, the parts being in a different position. Fig. 11 is 20 a detail, being an elevation of the shifting-lever *a* and its spring. Fig. 12 is a section at line 12 of Fig. 11. Figs. 13 and 14 are details, being views of the switch-arbor. Figs. 1 to 7, inclusive, are somewhat enlarged. 25 Fig. 8 to 14, inclusive, are about three times full size.

Winding and setting devices which can be brought into position and operated by a longitudinally-movable stem-arbor or stem-key 30 are common, and cases for movements containing such devices are called "pendant-set" cases. A stem-key which is not longitudinally movable is frequently used for winding and setting, the setting devices being 35 brought into position by a lever operated by hand, and cases for movements containing such devices are known as "lever-set" cases.

The leading objects of my invention are to 40 provide improved devices by means of which a stem-driven train in a pendant-set case can be brought into engagement either with a dial-wheel or the winding-wheel at pleasure, and to provide a watch-movement containing the said improved devices, with devices which 45 adapt it to be used in an exclusively lever-set case as well as in a pendant-set case, which

I accomplish, as illustrated in the drawings and hereinafter described.

That which I claim as new will be pointed out in the claims.

In the drawings, A represents a portion of the center band of a watch-case provided with a pendant and a longitudinally-movable stem-arbor, which may be constructed in any known suitable manner, and therefore I have not 55 shown or described them in detail.

B is the top plate.

C is the barrel-bridge. The upper plate is not shown; but it and the barrel-bridge are both supported by the plate B. The two 65 plates are recessed on their insides to receive the train. This construction, however, is made the subject of another application, and therefore these parts will not be here more fully described.

E is the stem-arbor or stem-key.

F is a yoke pivoted upon a hub and held by a cap and screw, as usual. At one end of this yoke there is a wheel G to engage with a wheel attached to the mainspring-arbor. At 75 the other end of the yoke is pivoted another wheel H, which can be made to engage one of the dial-wheels. These two wheels G H are driven by an intermediate wheel, which is driven by the pinion I, as usual, which 80 pinion is upon the piece which receives the inner end of the stem arbor or key, and is supported in the sleeve v, which is supported in a bearing formed in the barrel-bridge and plate B.

a is the lever that shifts the yoke when the movement is used in a pendant-set case. One end of this lever is pivotally secured at *b* upon a wall formed in the barrel-bridge. The 85 other end is free.

c is a spring, which, as shown, is made integral with the lever *a*.

d is a recess or groove in the lever *a*.

e is a pin which serves the purpose of a stop.

f is a pin, which is secured to the yoke F and passes through a slot or hole in the plate B and projects beyond the inside of such plate. The end of this pin is beveled, and it is so arranged that the free end of the shifting-lever *a* can come in contact with and pass over such inclined end.

g is a sliding pin with which the inner end of the stem arbor or key can come in contact to push it inward. The inner end of this pin is beveled and arranged to engage with a 5 bevel r on the edge of the lever a. (See Fig. 5.)

h is a switch-arbor, one end of which is supported in the plate D. The other end passes through the barrel-bridge, and is provided with a notch to receive a screw-driver for the purpose of partially rotating the same. 10

i is a pin which passes through the arbor h and projects from opposite sides thereof. One end of this pin is beveled to facilitate its 15 passage into the groove d in the lever a.

J is a lever for the purpose of moving the yoke, so that the wheel II will engage with the dial-wheel. This lever is pivoted at j, and is provided with an arm k, which can be made 20 to act upon the yoke by drawing out the arm l at the other end of the lever. This lever is not designed to be used when the movement is in a so-called "pendant-set" case; but it is for use when the movement is used in a lever-set case. 25

In Fig. 1 are two letters P and L. When the notch in the switch-arbor h is in line with the letter P, the movement is adapted for use in the pendant-set case. When such 30 notch in the switch-arbor is in line with the letter L, the movement can be used in a lever-set case, as will be hereinafter more fully described.

s is a spring which acts on the yoke F. 35 t is a spring which acts on the lever J.

The operation is as follows: Suppose the movement to be in a pendant-set case, the switch-arbor h being in the position shown in Figs. 1 and 4 and the stem-arbor pushed in 40 as shown in Fig. 8, which will force the beveled end of the sliding pin g over the incline r on the edge of the lever a. Then the free end of the lever will be forced away from the plate B and pin f, and the spring s will bring 45 the yoke into such position that the wheel G will engage with the winding-wheel attached to the mainspring-arbor, which is the normal position of the parts, as shown in Fig. 10. If now the stem-arbor be withdrawn a little, as shown in Fig. 7, the action of the 50 spring c will cause the free end of the lever a to pass over the incline upon the end of the pin f, as shown in Fig. 9, which will force the yoke into such position that the wheel H 55 will engage with one of the dial-wheels, ready for setting. By again pushing in the stem-arbor the free end of the lever a will be again carried away from the pin f, and by the action of the spring s the wheel G will be again 60 brought into engagement with the winding-wheel. It will be observed that the shifting-lever a works at right angles to the stem-key.

If it be desired to use the movement in a

lever-set case, the lever a can permanently be brought out of action by turning the switch-arbor h until the notch in the end thereof comes in line with the letter L, which will cause the beveled end of the pin i to enter the groove d in the lever a, which will carry the free end of such lever a away from the 70 plate B, bringing such lever a into an inoperative position, and then the spring s will bring the yoke into the position in which the wheel G will be in engagement with the winding-wheel. The inclined end of the pin i in 75 the switch-arbor comes in contact with the switch e when the switch-arbor is in the position which it is to occupy when the movement is to be used in a lever-set case, and the other end of such pin i comes in contact with the same stop when the switch-arbor is in the 80 position which it is to occupy when the movement is to be used in a pendant-set case.

By means of the lever J the position of the yoke can be shifted, bringing the wheel II 85 into engagement with one of the dial-wheels, ready for setting.

What I claim as new, and desire to secure by Letters Patent, is as follows:

1. In a stem winding and setting watch, a 90 lever a acting at right angles to and adapted to be acted on by a stem-key, in combination with a pin f on the yoke F, which pin f passes through a slot or hole in the plate B, and is arranged to be acted on by the shifting-lever, 95 substantially as and for the purpose specified.

2. In a stem winding and setting watch, a stem-key having a beveled point, in combination with shifting-lever a, with one edge of which the stem-key engages, a spring s, and 100 a pin f, connected with the yoke F, which pin passes through the plate B, and is arranged to be acted on by the shifting-lever a, substantially as and for the purpose specified.

3. In a stem winding and setting watch, 105 the combination of a switch-arbor h with the shifting-lever a, for the purpose of holding the lever a out of action when desired, whereby the same movement is adapted to be used either in a pendant-set case or in an exclusively lever-set case, substantially as specified.

4. In a stem winding and setting watch, a switch-arbor h, provided with a pin i, in combination with a shifting-lever a, provided with a groove d, substantially as and for the 115 purpose specified.

5. In a stem winding and setting watch, a shifting-lever a, in combination with a switch-arbor h, constructed and arranged as described, whereby such switch-arbor can be 120 operated from the outside of the plate B, substantially as specified.

ALBERT TROLLER.
